UNITED STATES PATENT OFFICE.

JAMES ALLINGHAM, OF CHICAGO, ILLINOIS.

MECHANICAL MOVEMENT.

931,713.

Specification of Letters Patent. Patented Aug. 24, 1909.

Application filed March 14, 1908. Serial No. 421,073.

To all whom it may concern:

Be it known that I, JAMES ALLINGHAM, a citizen of the United States, residing at Chicago, in the county of Cook and State of Illinois, have invented certain new and useful Improvements in Mechanical Movements, of which the following is a specification.

This invention relates to improvements in a mechanical movement which is applicable for use for various purposes, but in the present instance, I have shown and will herein-after describe it in connection with and for operating the flushing-valve and seat of a water-closet; yet I desire it to be understood that I do not wish to be limited in the use of the invention to any specific purpose for which it may be employed, nor do I wish it to be understood as limiting myself to the exact construction and arrangement of the various parts of the device as herein shown, as I may employ it for any purpose for which it may be adapted, and may vary the details of the construction without departing from the principle and spirit of the invention.

25 The principal object of the invention is to provide a mechanical movement of the above-described character, which shall be simple and inexpensive in construction, strong, durable, efficient and substantially noiseless in operation, the parts of which shall be so made and arranged as not likely to get out of order through use.

A further object of the invention is to provide a movement, which, when used in connection with and for operating a flushing-valve and water-closet-seat conjointly, as shown in the drawing, or for performing either of said functions separately, may be adjusted with respect to said parts so as to give them the proper or desired movement.

40 Other objects and advantages of the invention will be disclosed in the subjoined description and explanation.

The invention consists in certain peculiarities of the construction, novel arrangement, and operation of the various parts thereof, as will be hereinafter more fully set forth and specifically claimed.

In order to enable others skilled in the art 50 to which my invention pertains, to make and use the same, I will now proceed to describe it, referring to the accompanying drawing,

which serves to illustrate the invention, and in which—

Figure 1 is a view partly in section and partly in elevation of a mechanical movement embodying my invention, showing it applied to a flushing-valve and a part of the bowl of a water-closet, illustrating by continuous lines the positions the parts will assume when the valve is closed and the closet-seat is in its normal or raised position, and by dotted lines the positions the parts will assume in the act of opening the valve and when the seat is occupied or in its lowered position; Fig. 1^a is a similar view of like parts showing by continuous lines the positions the parts will assume in the act of opening the valve and when the seat is occupied or in its lowered position, and by dotted lines the positions the parts will assume when the valve is closed and the closet-seat is in its normal or raised position; Fig. 2 is a detached perspective view of the hinge-members which operate the valve mechanism and coöperate with other parts to control the movement of the lever which operates the seat; Fig. 3 is a detached perspective view of the operating lever; Fig. 4 is a similar view of the adjustable bracket, to the upper portion of which one of the members of the hinge is pivotally connected; and Fig. 5 is a fragmental view partly in section and partly in elevation of a portion of the flushing-valve and a part of the operating-lever, showing a modification in the construction of the movement.

Like numerals of reference, refer to corresponding parts throughout the different views of the drawing.

The reference numeral 10 designates a portion of the bowl of a water-closet, on the upper rear portion of which is mounted a bracket 11 which may be fixed thereto in any suitable manner, and has in its lower portion an opening in which a pipe section 12 leading from the discharge opening of the flushing-valve into the bowl 10, or so as to communicate with the cavity of the latter, is located. Mounted on the outer portion of the pipe section 12 is a flushing-valve 13 which may be of the ordinary or any preferred construction and may have communication with a supply of water through

an inlet pipe 14 located at its bottom. The upper portion of the bracket 11 is provided with two spaced apart upwardly extending lugs 15, only one of which is herein shown, 5 between which lugs the front portion of the operating-lever 16 is fulcrumed on a pin 17 to which also the rear portion of a plate 18 secured to the closet-seat 19 is pivotally secured.

10 As is clearly shown in Figs. 1 and 3 of the drawing the operating-lever 16 is formed between its ends with an opening 20 for the reception of a portion of the flushing-valve 13, and said lever also has at its rear portion 15 a longitudinally extending slot 21 which communicates at its inner end with the opening 20 and is for the purpose to be presently explained. On each side of the slot 21 the lever is provided with a recess 22, 20 each of which has at its bottom an inward extension 23 provided with apertures 24 for the reception of bolts 25 used for securing the base of the adjustable bracket to said extensions. The front part of the lever 16 25 is preferably provided with a transverse extension 26 which, as shown, is of less thickness than the body of the lever, and has at about its middle an opening 27 for the reception of a screw 28 which may have on its 30 upper end a swiveled head 29 to rest against the lower surface of the seat 19 so as to regulate the inclination of the latter with respect to the lever. The operating-lever 16 also is provided between its front end and the 35 opening 20 therein with an opening 30 in which is located a screw 31, the lower end of which is adapted to rest on the upper portion of the bracket 11 and is used to regulate the downward movement of the lever. Secured 40 to the rear portion of the lever 16 and on the upper surface of the extensions 23 thereof, when the same are used, is the base 32 of the adjustable bracket, which supports at its 45 upper end the means for operating the valve mechanism. This bracket consists of the base 32 and two spaced apart upright members 33 each of which has in its upper end a transverse opening 34 for the reception of a pin 35 on which one of the members of the 50 hinge is secured. The base 32 of the adjustable bracket is provided with a pair of slots 36 for the reception of the bolts 25 which are passed through the same, as well as through the openings 24 in the front part 55 of the lever 16 so as to adjustably secure the bracket in position. Between the slots 36 the base 32 of the bracket is provided with an opening 37 for the reception of a hollow nut 38 which is provided with oppositely 60 disposed projections 39 to rest on the upper surface of the base 32 on each side of the opening 37 therein, thus permitting of a slight movement or oscillation back and forth of the nut 38, which it will be understood 65 stood is somewhat smaller than the opening

37 in which it is located. This nut is in screw engagement with the upper portion of a hollow piston rod 40, which has on its lower end a piston or plunger 41 which is provided at its periphery with a flexible washer or valve 43 which may be held in place on the plunger by any desired means. 70

As is clearly shown in Fig. 1 of the drawing the plunger 41 is located in a cylinder 44 which is shown as being pivotally supported 75 at its lower end on an extension 45 projecting from the rear portion of the valve 13, but it is obvious that it may be otherwise pivotally supported. Surrounding the piston rod 40 within the cylinder 44 is an expansion spring 46, one of the ends of which rests against the top of the cylinder or casing 44 and the other end against the upper surface of the plunger. Located in the tubular piston rod 40, which is internally screw-threaded and which has at a suitable distance above the plunger 41 a port 47, is a screw-threaded rod 48 which may be turned by means of a screw-driver or other instrument inserted through the hollow nut 38 and 80 into the other end of the piston rod 40 so as to regulate the size of the port 47, which may be done by turning the rod 48 in the proper direction. Within the casing or cylinder 44 is located a quantity of oil, glycerin, or other 85 suitable fluid, which, in the downward movement of the plunger 41, will be caused to pass up through the port 42 and out through the port 47, and in the upward movement of said plunger the fluid will pass between the 90 periphery of the plunger 41 and the walls of the cylinder, for it will be understood that the flexible washer or valve 43 will permit of the passage of the fluid in the upward movement of the plunger, but will prevent its 95 passage at the periphery of the plunger in the downward movement thereof. Secured to the rear upper portion of the valve-casing 13 is a horizontally disposed rod 49 which has its free portion screw-threaded to engage nuts 50 mounted thereon. The inner portion of the rod 49 has surrounding it a spring 51 which rests at one of its ends against the valve-casing 13 and at its other end against a washer 52 which is adapted to rest 100 against the inner surface of the longer hinge-member 53 which is pivotally secured at its lower end to an extension 54 on the plunger (not shown) of the valve 13, which extension projects through a vertical opening in the 105 rear portion of said valve-casing. The member 53 of the hinge is provided with a longitudinally extending slot 55 through which the rod 49 is extended, and has hinged to its upper end one end of a shorter member 110 56, the other end of which is pivotally connected by means of the pin 35 to the upper portion of the uprights or arms 33 of the adjustable bracket. 115

In Fig. 5 of the drawing I have shown a 120

modification in the construction of the movement, which consists in employing, instead of the hinged connection consisting of the pieces 53 and 56 shown in Figs. 1 and 2, a single piece connection 57 which is pivotally connected at its lower end to the movable part or extension 54 on the plunger of the valve end 13, and has its upper portion provided with a cam-race 58 for the reception 10 and operation of the pin 35 on the upper part of the adjustable bracket. In this modified construction the piece 57 may be actuated by a spring 51 as in the other construction, and its rearward movement may 15 be restricted or regulated by means of nuts 50 on the rod 49 as in the first above-described construction.

From the foregoing and by reference to the drawing it will be clearly understood and 20 readily seen that when the movement is employed in connection with and for operating the flushing-valve 13 and seat 19 of a water-closet the parts may be arranged and supported as shown in Fig. 1 and above-described, and that while in the positions shown by continuous lines in said figure the seat 19, which may have on its lower surface one or more buffers 19^a, will be held in an inclined position above the bowl 10 by reason 25 of the tension of the spring 46 acting on the plunger 41 in the cylinder or casing 44 when said construction for actuating the lever 16 is employed.

When downward pressure is applied to the 30 seat 19 it is apparent that the parts will assume the position indicated by the full lines, see Fig. 1^a, in which operation the front end of the lever will be depressed while its other end will be elevated, thus, through the instrumentality of the piston-rod 40, raising the plunger 41, thereby contracting the spring 46 and permitting the actuating fluid in the upper portion of the cylinder 44 to pass into the lower portion thereof at the periphery of the plunger, the flexible washer or valve 43 being employed for this purpose. When the parts are in the last-named position it is apparent that the members 53 and 56 of the connection uniting the arms 33 of 35 the bracket and the movable part 54 of the valve 13 will be brought into alinement with the spring 51, and will be so retained until pressure is removed from the seat 19, when by reason of the expansion of the spring 46 40 against the plunger 41, the rear end of the lever 16 will be forced downwardly, thus carrying the movable part 54 and its connection with the bracket to the dotted position shown at 60 (see Fig. 1), in which operation it will be understood that the fluid in the 45 lower part of the cylinder 44 will be forced up through the ports 42 and 47 into the upper portion thereof, and also in said operation the member 53 will strike one of the nuts 50 on the rod 49 and throw the members 53 and

56 out of alinement or off of dead center, as shown at 61 in Fig. 1 of the drawing, when the valve 13 will be fully opened to permit of the discharge to the pipe 12 of the flushing fluid, and will gradually rise to the point indicated by continuous lines in Fig. 1. As before stated, the valve 13 may be of the ordinary or any well-known type, or, if desired, the plunger therein to which the extension or part 54 is connected may be actuated in a similar manner to the plunger 41 in the casing or cylinder 44, and for this reason it is deemed unnecessary to illustrate in detail the construction of the parts of the valve. 70

When the modified construction shown in Fig. 5 of the drawing is employed and the parts are in the positions shown by continuous lines, it will be understood that the seat 19 is in its elevated position as shown in Fig. 1, when by applying pressure to the seat the parts will assume the positions shown by dotted lines at 62, in which operation the connection 57 will remain stationary and the pin 35 will traverse the race 58 to the upper end thereof. As long as pressure is maintained on the seat the bracket carrying the pin 35 will remain in the last-named position, but as soon as pressure is removed from the seat the bracket will be moved downwardly to the position shown in continuous lines, in which operation the pin 35 bearing on the horizontally inclined portion 63 of the race will force the connection 57 to the dotted position shown at 64, in the beginning of which operation the commencement of the opening of the flushing-valve will be performed, and said valve will be completely opened when the point at 64 is reached, at which time the connection 57 will strike one of the nuts 50, which will prevent its further rearward movement, thus causing the pin 35 to ride over the elbow of the part 63 and permit the connection 57 to be elevated to the position shown by continuous lines, or its normal position. 80

Having thus fully described my invention, what I claim as new, and desire to secure by Letters-Patent, is—

1. A mechanical movement consisting of a lever fulcrumed near one of its ends, spring 115 actuating means near its other end, a bracket on the lever near said actuating means, a spring-actuated connection loosely united at one of its ends to the bracket and at its other end to a movable part, and means to restrict 120 the movement of said connection.

2. A mechanical movement consisting of a lever fulcrumed near one of its ends, spring 12 actuating means near its other end, a bracket on the lever near said means, a spring-actuated connection loosely united at one of its ends to the bracket and at its other end to a movable part, and means to restrict the movement of said connection.

3. A mechanical movement consisting of a 130

- lever fulcrumed near one of its ends, spring actuating means near its other end, an adjustable bracket on the lever near said means, a spring-actuated connection loosely united at one of its ends to the bracket and at its other end to a movable part, and adjustable means to restrict the movement of said connection.
4. A mechanical movement consisting of a lever fulcrumed near one of its ends, spring-actuating means near its other end to actuate it in one direction, a bracket on the lever near said means, a support independent of the lever and between its ends, a connection loosely united at one of its ends to the bracket and at its other end to a part movable on said support, a projection extended from the support beyond the connection but near the same, and means on said projection to restrict the movement of the said connection.
5. A mechanical movement consisting of a lever fulcrumed near one of its ends, spring-actuating means near its other end to actuate it in one direction, an adjustable bracket on the lever near said means, a support independent of the lever between its ends, a spring-actuated connection loosely united at one of its ends to the bracket and at its other end to a part movable on said support, a projection extended from the support beyond the connection but near the same, and means on said projection to restrict the movement of the said connection.
6. A mechanical movement consisting of a lever fulcrumed near one of its ends, spring-actuating means near its other end to actuate it in one direction, an adjustable bracket on the lever near said means, a support independent of the lever between its ends, a spring-actuated connection loosely united at one of its ends to the bracket and at its other end to a part movable on said support, a projection extended from the support beyond the connection but near the same, and means on said projection to restrict the movement of the said connection.
7. A mechanical movement consisting of a lever fulcrumed near one of its ends, actuating means near its other end, a bracket on the lever near said actuating means, a connection consisting of a plurality of hinged members, the upper one of which is loosely united to the bracket and the lower one pivotally united to a movable part, and means to restrict the movement of said connection.
8. A mechanical movement consisting of a lever fulcrumed near one of its ends, means near its other end to actuate it in one direction, an adjustable bracket on the lever near said means, a support independent of the lever between its ends, a spring-actuated connection consisting of a plurality of hinged members, the upper one of which is loosely united to the bracket and the lower one of which is pivotally united to a part movable on the said support, a projection extended from the support beyond the connection but near the same, and means on said projection to restrict the movement of the said connection.
9. A mechanical movement consisting of a lever fulcrumed near one of its ends, spring actuating means near its other end to actuate it in one direction, a bracket on the lever near said means, a support independent of the lever, a connection loosely united at one of its ends to the bracket and at its other end to a part movable on said support, a projection extended from the support beyond the connection but near the same, and means on said projection to restrict the movement of the said connection.
10. The combination with the bowl of a water-closet, of an operating lever fulcrumed near one of its ends thereon and having an opening intermediate its ends, a flushing-valve located in said opening, a casing located near the rear end of the lever, a spring and fluid-actuated plunger located in said casing, means connecting the rear portion of the lever to said plunger, a bracket on the lever near said connecting means, a spring-actuated connection loosely united at one of its ends to the bracket and at its other end to a movable part on the valve, means to restrict the movement of said connection, and a closet-seat connected to the lever in front of its fulcrum point.
11. The combination with the bowl of a water-closet, of an operating-lever fulcrumed near its front end thereon and having an opening intermediate its ends, a flushing-valve located in said opening, a casing mounted near the rear end of the lever, a spring and fluid-actuated plunger located in said casing, means connecting the rear portion of the lever to said plunger, a bracket on the lever near said connecting means, a connection consisting of a plurality of hinged members, the upper one of which is loosely united to the bracket and the lower one pivotally united to a movable part, means to restrict the movement of said connection, and a closet-seat connected to the lever in front of its fulcrum point.
12. The combination with the bowl of a water-closet, of an operating-lever fulcrumed thereon near its front end and having an opening intermediate its ends, a flushing-valve located in said opening, a casing mounted near the rear end of the lever, a spring and fluid-actuated plunger located in said casing, a hollow piston-rod connected at one of its ends to said plunger and movably connected at its other end to the rear portion of the lever and having a port within the casing, a screw-threaded-rod located in the piston-rod to open and close the port therein, a bracket on the rear portion of the lever, a connection loosely united at one of its ends to the bracket and its other end to a part mov-

able on the valve, means to restrict the movement of said connection, and a closet-seat connected to the lever in front of its fulcrum point.

5. 13. The combination with the bowl of a water-closet, of an operating-lever fulcrumed thereon near its front end and having an opening intermediate its ends, a flushing-valve located in said opening, a casing 10 mounted near the rear end of the lever, a spring and fluid-actuated plunger located in said casing, a hollow piston-rod connected at one of its ends to said plunger and movably connected at its other end to the rear portion 15 of the lever and having a port within the cas-

ing, a screw-threaded-rod located in the piston-rod to open and close the port therein, a bracket on the rear portion of the lever, a connection consisting of a plurality of hinged members, the upper one of which is loosely 20 united to the bracket and the lower one pivotally united to a movable part on the valve, means to restrict the movement of said connection, and a closet-seat connected to the lever in front of its fulcrum point.
